AUTOMATIC HUMIDIFIER

Charles M. Weeks, Chevy Chase, Md.

Application September 5, 1939, Serial No. 293,503

2 Claims. (Cl. 237—78)

This invention relates to an automatic humidifier designed to maintain a body of water in an open container in thermal contact with a radiator or other heat emitting element forming a

5 part of a house heating system, in order that the water may be heated and consequently vaporized to cause it to pass into the air of the room in which the radiator is located.

An automatic humidifier of this type is desirable 10 in order to maintain the air sufficiently moist or at the proper humidity not only to provide for human comfort, but to prevent drying out and disintegration of walls, furniture, pictures or other objects.

15 It is an object of the invention to provide a simple, inexpensive and efficient humidifier capable of being easily and simply applied to a radiator of a hot water heating system without having to drain the radiator or alter the system 20 in any way other than to merely open the air vent.

Another object of the invention is to provide means to automatically maintain the proper 25 amount of water in the vaporization or evaporation receptacle.

A still further object of the invention is to provide a humidifier which will automatically vent the trapped air in a radiator of a hot water heating system.

30 A still further object of the invention is to provide an automatic humidifier of the character stated applicable to a steam heating system as well as a hot water system.

Other objects and the nature and advantages 35 of the invention will be apparent from the following description taken in conjunction with the accompanying drawing, wherein:

Fig. 1 is a fragmentary perspective illustrating the invention applied to the radiator of a hot 40 water heating system;

Fig. 2 an enlarged fragmentary side elevation partly in section with the control valve in open position;

Fig. 3 an enlarged longitudinal section of the 45 control in closed position; and

Fig. 4 is a fragmentary detail illustrating the type of control used with a steam heating system.

Referring to the drawing, a conventional radiator 40 of a hot water heating system is provided with an air vent 11 having a depending discharge outlet or nozzle 12, with a needle valve 13 mounted by means of a threaded head in the air vent fitting and with a polygonal head 14 adapted to be engaged by a key for rotating the head and unseating the valve so that entrapped

air may pass outwardly downwardly through the discharge nozzle until the trapped air is all exhausted and water from the system begins to escape, whereupon the valve may be closed.

In order that the air of the room in which the radiator is located may be kept at the proper humidity, an open top container or receptacle 15 is adapted to be mounted, by hooks 29 or other supports, in thermal contact with the radiator. The receptacle 15 is supplied with water from 10 the radiator through a tube 16 to maintain the water level of the receptacle at a predetermined value.

In order that the humidifier may be applied while the heating system is in operation the 15 connection from the radiator to the vaporizing receptacle or container 15 is made directly to the discharge nozzle or vent fitting 11 and the needle valve 13 unscrewed to provide open communication between the radiator and the receptacle, a control 17 being mounted in the receptacle and being actuated by moisture to cause expansion of an element to close the valve and shut off water to the receptacle as will be hereafter described.

The control 17 comprises a perforated sleeve having a hook or bracket 18 at its upper end extending over the upper rim of the container for supporting the control in proper position. Within the receptacle there is a cylindrical expansive 30 element 19, of oak wood or other type of expansive material. This expansive element is adapted to absorb water and expand to move a valve body 20 downwardly into contact with its valve seat 21, the valve body 20 being normally held in its 35 raised position by means of a spring 22.

The upper end of the expansive element 19, rests against an adjusting screw 23 mounted in a head 24 by means of screws 24', thus when water has been absorbed by the expansive element 19, its upper end abutting the screw will not be permitted to move upwardly; therefore, it expands downwardly and causes the valve 21 to move toward its seat and when it is sufficiently expanded it will close the valve and cut off flow 40 of water into the container 15. As shown in Fig. 2, the water level is slightly below the normal water level, the expansive element 19 is therefore contracted, the valve is open, and water is ready to flow into the container 15. The valve 50 is in the opposite position in Fig. 3.

In order to connect the supply tube 16 to the radiator, the upper end of the tube is provided with an enlarged end portion 25 with its wall relatively thin in order to receive in a water tight 55

manner the depending discharge nozzle 12 of the vent fitting 11. This enlarged end 25 may likewise be provided with a screen for preventing rust or other particles from passing into the pipe 5 16. The enlarged end 25 of the supply pipe is likewise provided with a yoke 27 and a screw 28. The yoke is constructed to fit over the vent fitting 11 with the screw 28 connecting the parts in a manner to prevent leakage therebetween. 10 10 In applying the invention to the conventional radiator of a hot water heating system, the receptacle 15 is attached in good thermal contact to the radiator by means of the hooks 29. The yoke 27 on the upper end of the supply pipe 16 15 is placed over the vent fitting 11 with the discharge nozzle of the vent fitting extending slightly into the enlarged end 25 of the supply pipe. Thereupon the screw 28 is tightened so that there will be no leakage at the joint between the vent 20 fitting and the enlarged end 25 of the supply pipe. The pan or container 15 is filled to the desired water level so that the expansive element 19 is allowed to swell and close the valve in the supply line 18. Thereupon a key is applied to the 25 polygonal head 14 of the needle valve 13 and the needle valve unseated to establish communication between the interior of the radiator and the control valve 11. No water will pass into the receptacle 15 because the valve 23 is tight against the seat 24. When the water in the receptacle has evaporated until the lower end of the expansive element 19 is not wet, contraction of the 30 expansive element will occur thereby unseating the valve and allowing the pan to be filled automatically until the water rises sufficiently to wet the expansive element whereupon the valve will be closed. 35

A closure such as a cap 30 may be placed over the outer end of the vent fitting 11 in a manner 40 to cover the polygonal needle valve operating head, the cap 30 being provided with a screw 31 for securing it in place and with a gasket 32 for preventing leakage.

The above construction is also applicable to a 45 radiator of a steam heating system by placing the valve in the supply pipe beneath the water level so that steam coming through the pipe may be condensed. As shown in Fig. 4, the receptacle 15 is provided with a control element of similar 50 but slightly different construction than that of the preceding figures including a sleeve 33 provided with perforations 34 (like the control 17) through which water may reach an expansive element 35, steam being admitted through a supply pipe 36 when the valve 37 on the lower end of a valve stem 38 is off its seat. The upper end of the sleeve 33 is provided with a cap 39 having an adjusting screw 40 threaded therethrough in 55 engagement with an expansive element 35 which may be similar to the expansive element 19 previously described. The control is supported by

means of a hook or bracket 41 which extends over the upper end of the receptacle 15.

In operation, steam entering the receptacle 15 through the supply pipe 36 will flow around the valve 37 into the water within the container 15 5 to be condensed, the position of the valve 37 being subject to the dry or moist condition of the expansive element 35. When the expansive element is wet the valve will be closed and when dry it will be open. 10

It will be obvious to those skilled in the art that various changes may be made in this device without departing from the spirit of the invention and therefore the invention is not limited to what is shown in the drawing and described in 15 the specification but only as indicated in the appended claims.

What is claimed is:

1. In combination: a radiator adapted to be supplied with a moisture producing heating 20 fluid; a conduit for feeding said fluid from said radiator to a liquid producing evaporation receptacle positioned in heat exchange relationship with said radiator; means attached to said conduit including a valve and a substance adjacent said valve capable of expanding, when wet by contact with liquid and of contracting when out of contact with liquid; said valve and said substance being so positioned within said receptacle that the expansion of said 25 substance when in contact with a predetermined level of liquid in said receptacle will cause said valve to shut off the supply of fluid to said receptacle, said substance being effective when dried 30 by the evaporation of said liquid in said receptacle or when dried by the heat from said radiator to cause said valve to re-establish the flow of fluid from said radiator to said receptacle. 35

2. An automatic water feeding device comprising a conduit adaptable to connect the air vent 40 of a hot water radiator with a moisture producing and evaporating receptacle positioned in heat exchange relationship with said radiator; said conduit having one end provided with means for maintaining a fluid-tight connection with said air vent, the other end of said conduit having attached thereto a valve and a substance adjacent 45 said valve capable of expanding when wet by contact with water and of contracting when out of contact with water, said valve and said substance being adaptable to be so positioned within said receptacle that the expansion of said substance when in contact with a predetermined level of water in said receptacle will cause said valve to shut off the supply of water through said 50 conduit from said radiator to said receptacle, said substance being effective when dried by the evaporation of water in said receptacle or when dried by heat from said radiator to open said valve to 55 re-establish the flow of water from said radiator to said receptacle.
